UNITED STATES PATENT OFFICE.

BERT JACOBS, OF WATERLOO, IOWA.

ROBE-HOLDER CLAMP.

1,300,273.

Specification of Letters Patent. Patented Apr. 15, 1919.

Application filed April 4, 1918. Serial No. 226,761.

To all whom it may concern:

Be it known that I, BERT JACOBS, a citizen of the United States, residing at Waterloo, in the county of Blackhawk and State 5 of Iowa, have invented certain new and useful Improvements in Robe-Holder Clamps; and I do hereby declare the following to be a full, clear, and exact description of the invention, such as will enable others skilled in 10 the art to which it appertains to make and use the same.

This invention relates to improvements in robe holder clamps and has for one of its 15 objects the provision of a device of this character especially adapted for securing a lap robe to the seat of a vehicle over the occupant or occupants of the seat, thus relieving the occupants of the annoyance of manually holding the robe over the lap.

Another object of this invention is the provision of means connected to the seat and having flexible elements secured thereto carrying clamps adapted to grip the edge of a lap robe for the purpose of supporting the 25 lap robe about the occupants of the seat.

A further object of this invention is the provision of a robe holder clamp of the above stated character, which shall be simple, durable and efficient, and which may 30 be manufactured and sold at a comparatively low cost.

With these and other objects in view, as will become more apparent as the description proceeds, the invention consists in certain novel features of construction, combination, and arrangement of parts as will be hereinafter more fully described and claimed.

For a complete understanding of my invention, reference is to be had to the following description and accompanying drawings, in which:

Figure 1 is a front elevation of a robe holder clamp constructed in accordance with 45 my invention,

Fig. 2 is a rear elevation partly in section of the same;

Fig. 3 is a vertical sectional view illustrating the means of securing the flexible 50 elements to the seat,

Fig. 4 is a sectional view taken on the line 4—4 of Fig. 2,

Fig. 5 is a sectional view taken on the line 5—5 of Fig. 2,

Fig. 6 is a sectional view taken on the line 6—6 of Fig. 2,

Fig. 7 is a detail sectional view of one of the clamps,

Fig. 8 is a fragmentary front elevation of a modified form of my invention, 60

Fig. 9 is a sectional view of the same taken on line 9—9 of Fig. 8.

Referring in detail to the drawings, the numeral 1 indicates an attaching member consisting of sections 2 and 3. The sections 65 2 and 3 are slidably connected by means of bands 4 and the section 2 has a plurality of teeth 5 formed thereon. A pair of ears 6 are formed upon the section 3 and has pivoted thereto a lever 7 having an eccentric portion provided with teeth 8 adapted to bite into the teeth 5 for holding the sections 2 and 3 in adjusted position in relation to each other.

The attaching member 1 is adapted to be 75 placed across the rear face of the back 9 of the seat 10 and has secured thereto supporting members 11 which have their upper ends bent to form hooks adapted to engage over the upper edge of the back 9 of the seat 10 80 and are covered with felt or other suitable material 12 to prevent marring or injuring of the upholstering upon the seat or the wood work thereof. If desired dust covers 13 may be placed over the seat portion and back 9 and secured to the back 9 by placing the supporting members 11 thereover as clearly illustrated in Fig. 3. Brackets 14 are secured to the hook portions of the supporting members 11 and have connected thereto 90 straps 15. The straps 15 have connected thereto suitable clamps 16 consisting of resilient arms 17 that are adapted to be forced in engagement with each other by means of rings 18 to grip the upper edge of the lap robe 19 to support the same over the seat and the occupants thereof. 95

A member 20 is formed upon the attaching member 1 and depends downwardly therefrom and has hinged thereto a substantially L-shaped bracket 21 provided with a set bolt 22 in its horizontal arm portion. The horizontal arm portion is adapted to swing under the lower edge of the seat as illustrated in Fig. 4 and by turning the set 100 bolt 22 in engagement therewith, the device 105 will be firmly secured to the seat.

From the foregoing description taken in connection with the accompanying drawings, it will be noted that a device has been 110 provided which can be readily and conveniently applied to the seat of a vehicle for the

purpose of supporting and holding a lap robe 19 over the occupants thereof thereby leaving the occupants' hands free for other uses.

5 The aforescribed device is especially adapted for application upon the front seat of a vehicle.

Referring to my modified form of invention, as disclosed in Figs. 8 and 9, it consists 10 of a device especially adaptable for the rear seats of a vehicle wherein the rear curtain to the top of the vehicle is usually attached to the rear face of the back portion of the seat and which is not shown.

15 Plates 23 are secured to the upper edge of the back 24 of the rear seat and have secured thereto substantially U-shaped members 25. The straps 15 are connected to the U-shaped members so that the clamps 16 may be readily 20 attached to the lap robe for the purpose of supporting the same over the seat.

While I have shown and described the preferred embodiment of my invention, it will be understood that minor changes in construction, combination, and arrangement of parts may be made without departing from 25 the spirit and scope of the invention as claimed.

What I claim as new is:—

30 1. A robe holder comprising an attaching member, supporting members carried by

Copies of this patent may be obtained for five cents each, by addressing the "Commissioner of Patents.
Washington, D. C."

said attaching member and bent to form hooks for engagement with the upper edge of the seat, straps connected to said supporting members and clamps carried by said 35 straps.

2. A robe holder comprising an attaching member consisting of a pair of adjustable sections, means slidably connecting said sections together, teeth formed on one of said sections, an eccentric lever having teeth pivoted to the other section and adapted to coöperate with the teeth and locking the sections against movement, means securing the attaching member to a seat, straps connected 40 to said means, and clamps carried by said straps.

3. A robe holder comprising an attaching member, supporting members connected to the attaching member and engaging the upper edge of the seat, a bracket hinged to the attaching member, a set screw carried by said bracket and adapted to be turned into engagement with the lower edge of the seat, straps secured to the supporting members 50 and clamps connected to the straps.

In testimony whereof I affix my signature in presence of two witnesses.

BERT JACOBS.
